UNITED STATES PATENT OFFICE.

NYKOLA NAJKALYK, OF MYRNAM, ALBERTA, CANADA.

RAILROAD-JOINT.

1,278,986.

Specification of Letters Patent. Patented Sept. 17, 1918.

Application filed July 14, 1917. Serial No. 180,493.

To all whom it may concern:

Be it known that I, NYKOLA NAJKALYK, a subject of the King of England, resident of Myrnam, Province of Alberta, and Dominion of Canada, have invented certain new and useful Improvements in Railroad-Joints, of which the following is a specification.

This invention relates to improvements in rail connections, whereby the ends of adjacent rails may be rigidly engaged together so as to be prevented from movement, either longitudinally, vertically, or laterally.

One of the principal objects of the invention is to provide means whereby rails may be engaged in the manner stated without the use of fish or joint plates of any kind, and also to dispense with the use of bolts or like securing means.

20 This object is accomplished by the novel design, construction and combination of parts hereafter described and shown in the accompanying drawings, forming a material part of this disclosure, and in which:—

25 Figure 1 is a side elevational view of a pair of abutting rails, the ends of which are formed in accordance with the invention.

Fig. 2 is a transverse sectional view taken on line 2—2 of Fig. 1.

30 Fig. 3 is another transverse sectional view taken on line 3—3 of Fig. 1, the parts prior to adjusting being shown in dotted lines.

Fig. 4 is a side elevational view of the end of an abutting rail formed in accordance 35 with the invention.

Fig. 5 is a vertical sectional view through the end of the adjoining rail, and

Fig. 6 is a front elevational view of the rail shown in Fig. 4.

40 In the drawings, the heads of both rails are indicated by the numeral 10, the base 11 and stem 12.

The abutting ends of both rails are of a thickness corresponding with the head of the 45 rail, the adjacent portion 14 of one being recessed at 15, the horizontal overhanging part having a curved surface 16, from which extends a cylindrical stem or rod having formed upon opposite sides projections, respectively 19 and 20, while the abutting rail has an enlargement 24 and an extending element 25, formed with a recess 26, adapted

to engage with the curved extension 16, the latter acting in the manner of a key and preventing lateral dislocation.

55 A cylindrical opening 28 is formed axially in the rail end 24 and is provided with a slot 29 through which the projections 19 and 20 may pass as the rails are pressed endwise together; when the projections have 60 entered the transverse passages 30 and 32, the rails may be rotated one with respect to another, thus causing the projections 19 and 20 to engage within the recesses, thereby locking the two rails positively together.

65 As the stem 18 is receivable within the opening 28, it holds the rails together so that one cannot move relatively to the other, either up or down or sidewise, while the 70 projections 19 and 20 entering the passages 30 and 32 prevent the rails from being separated longitudinally.

Having thus described my invention, what I claim as new, and desire to secure by Letters Patent, is:—

75 1. The combination with a pair of abutting rails, of fixed lateral extensions at the ends thereof, a projection formed with the upper part of one of said rails, said projection having a convex lower surface, a corresponding recess formed in the lower part of the other rail, a cylindrical stem extending from said projection adapted to enter an axial opening formed in the other rail, and oppositely disposed integral keys formed on 80 said stem adapted to engage with corresponding recesses formed in the abutting rail, said stem being semi-rotatable within the mentioned axial opening.

85 2. In a rail joint connection, the combination with a pair of abutting rails, provided with end extensions, one of said extensions having a concave upper face and the other a convex lower face adapted to co-operatively engage a cylindrical stem extending from one of said rails adapted to enter an axial bore in the other rail, and lateral projections formed with said stem, whereby rotating one of said rails relative to the other causes the engagement of said projections in corresponding cavities formed in the other rail.

90 In testimony whereof I have affixed my signature.

NYKOLA NAJKALYK.
